(Cl. D52—1)

To all whom it may concern:

Be it known that we, James M. Gallant and Robert A. Fees, citizens of the United States, residing at Delaware and Radnor, respectively, in the county of Delaware, State of Ohio, have invented a new, original, and ornamental Design for a Drawing Guide, of which the following is a specification, reference being had to the accompanying drawing, forming a part thereof, in which

Fig. 1 is a plan view of a drawing guide, showing our new design.

Fig. 2 is an edge view of the guide shown in Fig. 1.

We claim:

The ornamental design for a drawing guide, substantially as shown.

JAMES M. GALLANT.
ROBERT A. FEES.
